UNITED STATES PATENT OFFICE.

RICHARD H. STEVENS, OF MUNHALL, PENNSYLVANIA.

SHEET-METAL PILING.

No. 866,082.

Specification of Letters Patent.

Patented Sept. 17, 1907.

Application filed January 11, 1904. Serial No. 188,470.

To all whom it may concern:

Be it known that I, RICHARD H. STEVENS, of Munhall, Allegheny county, Pennsylvania, have invented a new and useful Sheet-Metal Piling, of which the following 5 is a full, clear, and exact description, reference being had to the accompanying drawings, forming part of this specification, in which--

Figure 1 is a plan view of sheet metal piling constructed in accordance with my invention; Fig. 2 is a 10 side elevation; Fig. 3 is a horizontal section on a larger scale showing one of my improved interlocking members; Figs. 4 and 5 show modified corner constructions; Fig. 6 shows a modified form of sheet metal piling, and Fig. 7 shows a modified form of the interlocking piece.

15 My invention relates to the class of sheet metal pilings, especially that type wherein rolled commercial shapes are interlocked or connected together to form the piling.

20 The object of my invention is to provide an interlocking shape which can be used with flanged rolled shapes and will serve to connect them together to form the piling, without the use of rivets, bolts or other securing means, except at corners or turns in the pilings.

25 In the drawings in which I show my invention as applied to commercial rolled shapes, 2, 2 represent a pair of channels which are connected by my improved interlocking shape. This shape preferably consists of a web 3 having base flanges 4, 4 and provided with upper inwardly bent hooked flanges 5, 5. In other words the 30 shape consists substantially of an I-beam with upper flanges bent in to form hook flanges.

I preferably roll the interlocking shape of such dimensions that the flanges 6 of the channels 2 will be loosely engaged and held by the flanges of the shape. 35 Where the piling is used in mud, quick-sand, or dirt, the pilings may be used without packing, the shapes loosely engaging each other and being held by the hook flanges. Where the piling is used for shutting out water, the joints between channels and the interlocking 40 shapes are preferably packed by suitable packing material, 7 which is forced in between the base flange of the locking shape, and the web of the channel. In order to more securely hold such packing in position, I 45 preferably bend the base flanges of the interlocking shape inwardly to a slight degree, so that the space between the channel and the base flange of the shape will increase slightly in depth toward the web of the shape. The packing will thus be keyed or wedged in place. The driving in of this packing will thus make a water 50 tight joint. The water being on the outside of the piling, if water leaks into the space between the channel flanges and the web of the interlocking shape, its pressure will act upon the packing and tend to wedge it tighter by forcing it into the wedge-shaped space.

55 Where the face of the piling changes direction I may rivet one base flange 4' of the interlocking shape to the

flange 6 of the channel and then interlock the next channel flange 6 on the other side of the shape, so that one line of rivets only is necessary in changing direction in this manner. The corner may be a right angle, an 60 obtuse angle or in the form of a gradual change of direction producing substantially a curve. In changing the angle of the piling in the opposite direction I may adopt any one of several different connections; thus in Fig. 4, I show an angle 8 with its leg riveted to the flange 6 65 of the channel, the flange 9 of the angle interfitting with the interlocking shape on one side and taking the place of the channel flange on this side. From this point on, the construction is the same as before. Instead of this angle connection I may adopt that shown 70 in Fig. 5, in which the flange 10 of another channel 11 is riveted to the web of the last channel, this extra channel interlocking with the shape and the construction proceeding as before.

75 Instead of channels, I-beams may be used as shown in Fig. 6 of the drawing, in which case the interlocking shape has both of its flanges 4^a, 4^b bent so as to engage the flanges of the I-beams.

In Fig. 7 I show a form similar to Figs. 1 to 5, but with the base flanges 4^b of the interlocking shape in 80 their ordinary right angled position.

The advantages of my invention result from the obtaining of maximum strength for the piling with minimum weight metal. The structure consisting simply of rolled shapes, can be sold at low cost and put together 85 without the use of rivets or connections except at the corners or turns. Only two different shapes are used, namely the channel or other flanged shape, and the interlocking shape. The system is adapted to all kinds of pilings whether for shutting out water or otherwise, and the packing will be securely held in place, an 90 increase of water pressure packing it tighter.

The channels or I-beams may be built up instead of 95 rolled and many other changes may be made in the form of the shapes as well as in the form and size of the interlocking shape without departing from my invention.

I claim--

1. Sheet metal piling comprising flanged shapes, an interlocking shape having flanges arranged to engage the 100 flanges of the other shapes and lock them together, and packing between the interlocking shape and the other shapes; substantially as described.

2. Sheet metal piling comprising flanged shapes, an interlocking shape having hook flanges arranged to engage 105 and lock the flanges of the other shapes together, and packing between the interlocking shape and flange shape; substantially as described.

3. Sheet metal piling comprising flanged shapes, and an interlocking shape having flanges arranged to engage the 110 flanges of the other shapes, said flanges being arranged to provide wedge-shaped spaces to receive packing; substantially as described.

4. Sheet metal piling comprising channels and an interlocking shape having hooked flanges engaging the flanges

of the channels, and base flanges at the inner sides of the channels; substantially as described.

5. Sheet metal piling comprising channels, an interlocking shape having hook flanges engaging the channel flanges and inwardly bent base flanges on the interlocking shape arranged to provide wedge-shaped cavities between them and the channels, to receive packing; substantially as described.

6. A corner construction for sheet metal piling comprising a flanged shape, a supplemental flanged member riveted to the flanged shape and an interlocking shape engaging the riveted member and the flange of the next flanged shape; substantially as described.

7. A coupling for channel bars having in combination a web portion, means along one edge or end of the web portion for engaging the flanges of the channel bars and means along the opposite edge or end of the web for holding the flanges of the channel bars interlocked with the engaging members of the coupling; substantially as described.

8. Metal piling having in combination channel bars, a plate or web arranged between the flanges of adjacent

channel bars, means secured to the plate or web for engaging the flanges of the channel bars, and means for preventing the web from movement laterally of the channel bars; substantially as described.

9. Metal piling having in combination channel bars, a plate or web arranged between the flanges of adjacent channel bars, hooks secured to said web and adapted to engage the flanges of the channel bars and holding projections on the web for preventing the disengagement of the hooks and flanges; substantially as described.

10. Metal piling having in combination channel bars, a plate or web arranged between the flanges of adjacent channel bars, hooks secured to the web and engaging the flanges of the channel bars and flanges projecting at or approximately at right angles from the web and bearing against the plane sides of the channel bars; substantially as described.

In testimony whereof, I have hereunto set my hand.

RICHARD H. STEVENS.
